DESIGN FOR A COMBINATION BOTTLE AND CLOSURE CAP

Edward Horney, New York, N. Y.

Application July 17, 1937, Serial No. 70,489

Term of patent 3½ years

To all whom it may concern:

Be it known that I, Edward Horney, a citizen of the United States of America, residing in the city and State of New York, have invented a new, original, and ornamental Design for a Combination Bottle and Closure Cap, of which the following is a specification, reference being had to the accompanying drawing, forming part thereof, wherein,

Fig. I is a side elevation of the combination bottle and closure cap showing my new design;

Fig. II is a perspective view of the closure cap forming a part of the design shown in Fig. I;

Fig. III is a plan view of the bottle with the cap in place.

I claim:

The ornamental design for a combination bottle and closure cap, as shown and described.

EDWARD HORNEY.
